DESIGN FOR A LADY'S HANDBAG

Max Kaplan, Bridgeport, Conn., assignor to Max Kaplan, Benjamin Pressler, and Philip Kaplowitz, doing business as Empire Bag Company, Bridgeport, Conn.

Application August 15, 1942, Serial No. 107,940

Term of patent 7 years

To all whom it may concern:

Be it known that I, Max Kaplan, a citizen of the United States, residing at Bridgeport, in the county of Fairfield and State of Connecticut, have invented a new, original, and ornamental Design for a Lady's Handbag, of which the following is a specification, reference being had to the accompanying drawing, forming part thereof.

Fig. 2 is an elevational view of the other side thereof; and

Fig. 3 is an end elevational view thereof.

I claim:

The ornamental design for a lady's handbag, as shown.

MAX KAPLAN.
